UNITED STATES PATENT OFFICE.

JOHNATHAN R. FREEZE, OF MIDDLETOWN, OHIO, ASSIGNOR TO THE AMERICAN ROLLING MILL CO., OF NEWARK, NEW JERSEY.

PALLET.

1,202,046.

Specification of Letters Patent. Patented Oct. 24, 1916.

Application filed April 29, 1916. Serial No. 94,200.

To all whom it may concern:

Be it known that I, JOHNATHAN R. FREEZE, a citizen of the United States, residing at Middletown, Butler county, Ohio, have invented certain new and useful Improvements in Pallets, of which the following is a specification.

This invention pertains to pallets designed for use in transporting toward a drying situation such articles as bricks and the like, and relates particularly to details of construction of such pallets.

The invention will be readily understood from the following description taken in connection with the accompanying drawing in which:—

Figure 1 is a perspective view of a pallet exemplifying my present invention; Fig. 2 a longitudinal section of the same in the plane of line *a* of Figs. 1 and 3; and Fig. 3 a transverse section of the pallet in the plane of line *b* of Figs. 1 and 2.

In the drawing: 1, indicates a flat metallic plate forming the pallet proper; 2, downwardly turned ends of the plate to form legs permitting one pallet to rest upon another; 3, hand-holes in the downwardly turned portions 2; 4, downwardly bent portions extending along both side edges of the pallet proper and extending from near one of the down-turned ends 2 to near the other; 5, portions of the side edges of the pallet proper causing the pallet proper to be narrowed at its long edges; and 6, inturned flanges at the lower extremities of the down-turned end portions 2.

The ends of the pallet are the full width of the sheet from which the pallet is formed but it is narrowed for such portion of its

length as is turned down at 5. Therefore, 40 when a number of such pallets are placed side by side in touch with each other, the downturned portions 4 provide air spaces 5 between contiguous pallets and facilitate the drying, and the hand-holes 3 provide 45 air passages through which drying air may pass under the pallets proper and rise through the spaces 5. These pallets, especially when employed in the drying of brick, are piled one above the other, each pallet 50 carrying its layer of brick. The inturned edges 6 of the end portions of the pallet permit one pallet to rest fairly upon the pallet below it.

The improved pallet is formed of a single 55 piece of metal fully capable of withstanding the rough usage of pallets employed in the drying of brick, and capable of being easily straightened if any deformation is brought about by reason of rough usage. The downturned edges, 4 at the long edges of the pallet proper, not only provide air passages to facilitate the drying but serve also in longitudinally stiffening the pallet proper. 60

I claim:—

A pallet comprising, a pallet proper formed of a sheet of metal, downturned ends of the pallet having hand-holes, inturned portions of the downturned ends, and downturned edge portions of the pallet proper 70 extending from near its ends and causing the pallet proper to have a width less than that at its end, combined substantially as set forth.

JOHNATHAN R. FREEZE.
